UNITED STATES PATENT OFFICE

THOMAS E. MURRAY, OF BROOKLYN, NEW YORK; JOSEPH BRADLEY MURRAY, THOMAS E. MURRAY, JR., AND JOHN F. MURRAY, EXECUTORS OF SAID THOMAS E. MURRAY, DECEASED, ASSIGNEES TO METROPOLITAN ENGINEERING COMPANY, A CORPORATION OF NEW YORK

COMBINED HEATER AND RADIATOR

Application filed June 7, 1923. Serial No. 643,941.

The invention relates to heating appliances and particularly to articles such as household radiators and heaters.

The invention contemplates the production of an improved household heater or boiler made preferably of sheet or plate metal bent to a suitable shape so as to form a hollow structure through which a fluid such as steam or hot water can be circulated.

10 The invention is illustrated in the accompanying drawings in which Fig. 1 is a perspective view of a heater or boiler showing one embodiment;

Fig. 2 is a transverse section on 2—2 of Fig. 1;

Fig. 3 is a horizontal section on 3—3 of Fig. 2;

Fig. 4 is a detail section on 4—4 of Fig. 2;

20 Figs. 5, 6, 7 and 8 illustrate a modification of the heater shown in Figs. 1 and 2;

Fig. 9 shows a gas fired heater embodying the invention.

Referring in detail, first to Figs. 1 to 4 of the drawings, the principal water or steam 25 heating element of the heater or boiler 12 is supported on the fire box 14 which is formed with hollow walls so as to permit water to be circulated therethrough.

The fire box is preferably, though not necessarily, formed with a corrugated outer wall 16 providing greater radiating surface and stiffness and a smooth inner wall 18 spaced for example as in Fig. 4 to leave a hollow space 20 for circulation of the water used 35 in the heater. The fire box is provided with the usual grate bars 22, ash pit 24, combustion chamber or fire pot 26 and a frame 28 formed with suitable door openings for the ash pit and fire doors not shown.

40 The water or steam heating element 10 is held or positioned on the fire box 14 by a band 30 which may follow the contour of the corrugations 16 of the outer wall of the fire box.

45 The heating element 10 is formed preferably by bending or corrugating a sheet metal plate or plates to form a cellular structure such as shown in Fig. 3, comprising a series of hollow ribs 32 each including laterally extending walls 34 united integrally at 36 and

38 near their inner and outer ends respectively. Thus an extended radiating surface is provided and a stiff structure is formed, though the sheet metal may be comparatively thin.

55 When the water or steam heating element is subjected to internal pressure the tendency of such pressure is to distort or flex the sheet metal walls which it is understood are of comparatively light gauge stock. To counteract the effect of such pressure, I provide braces between the ribs on the outside of the structure and also certain braces or reinforcements within the structure. The braces within the structure are designed to prevent either 60 an inward or outward distortion of the structure due either to pressure or vacuum, that is to say, the reinforcement which I provide will prevent either collapse or outward buckling.

65 To prevent undue expansion or collapse of the hollow structure as above referred to, I secure Z bars 70 to the opposed walls 40, these bars being assembled so that their flanges 72 overlap. As thus arranged, it is apparent that such bars prevent any appreciable movement of the opposed walls 40 either inwardly or outwardly. While I have only illustrated Z bars 70 between the opposed walls 40 of the structure, it is to be understood 75 that when necessary such reinforcements can be used in the chambers 44 formed by the hollow ribs.

70 I also use in some instances a rectangular solid bar 74 for reinforcing the structure longitudinally and this bar is also useful 80 when assembling to insure that the parts are fabricated in the proper spaced relationship.

85 The heating element above described can be used either as a radiator in heating systems or as part of a heater or boiler itself. Fig. 2 shows the invention applied to a household heater, the hollow structure being connected with suitable water inlet 76 and hot water outlet 78 connected in the usual manner to the water supply and radiators in a hot water 90 heating system. This particular figure shows a fire box 14 arranged for a circulation of water between the walls 16 and 18 thereof as above described, the hollow fire box being connected with the hollow structure 10 by a 95 100

suitable pipe 80, fittings 82 and 84 and pipe 86. A suitable blow-off valve 88 is provided. Another pipe 90 connects the upper portion of the hollow fire box with an intermediate portion of the hollow structure 10 to provide for a suitable circulation of water between the two. This heater may be designed for use as either a steam or hot water unit.

Figs. 5 to 7 illustrate a heater similar to that shown in Figs. 1 to 4 except that the water or steam heating element 10 is supported by a fire box not adapted to have water circulated therethrough. The fire box of this heater comprises an outer corrugated wall 98 and inner wall 100. The walls 98 and 100 carry at the top an intermediate member 102 having an inclined dome 104 and a base portion 106 for supporting the hollow unit 10. This intermediate member is provided with a marginal flange 108 serving to hold the hollow structure 10 in place. The fire box is provided with a suitable grate 22^a and the usual door frames and other accessories as shown.

Fig. 8 illustrates a heater similar in design to that shown in Fig. 1 but having a comparatively larger fire box 14 suitable for fuels of great bulk.

Fig. 9 illustrates the heater 10 which is arranged to be heated by a gas burner 110 located within a base or casing 112, the heater being provided with a suitable water inlet pipe 114 and outlet pipe 116. A cap 118 fits over the top of the structure 10 and the design is such that the hot waste gases escape through a stack 120 having a suitable damper 122 therein.

The structure can be readily formed by bending a sheet or sheets of metal so as to form a multiple hollow ribbed or cellular structure 10. The ends of the walls of the hollow ribs can be readily pressed and welded together electrically or otherwise or soldered or the joint may be made by an electrolytic deposit and other portions of the structure can be similarly united to make the entire unit fluid-tight.

This type of heater structure is an improvement over those made by casting and the passages or cells of the structure can be made of much smaller sectional area so that the water or steam therein can be distributed in thin layers over an extensive multiple area. The walls can be made much thinner of sheet metal than it is possible to make them by casting, and the transfer of heat through such a thin sheet metal wall is much more rapid than through a thicker cast wall. This feature is of particular importance in heaters as they must frequently be brought from a comparatively cold to a hot state, it being the practice in operating household heating systems to bank the fires at night and allow the system to cool down considerably. With thin walled heaters herein de-

scribed, the heat is made available much more quickly when the fires are again opened up to heat the system.

What I claim is—

1. A combined heater and radiator comprising a sheet metal vessel for water to be heated, the wall of which is in the form of a series of hollow ribs, the hollows of which communicate with the central portion of the vessel, and partitions across the spaces between the outsides of said ribs forming flues for heating gases to heat the water in said vessel, means for generating heating gases and supplying said generated heating gases to said flues, said partitions being located at intermediate points in the width of said spaces and the partitions nearest the outer ends of said ribs having their outer faces exposed to the surrounding atmosphere and so disposed as to leave a substantial portion of the outer ends of the ribs exposed to the surrounding atmosphere.

2. Apparatus of the type described, which comprises a hollow water container structure having vertical hollow ribs extending laterally from a common central chamber and spaced to form channels open at one edge to the atmosphere, vertical walls in said channels to form heating flues in said channels and to leave the outer edges of the channels open to the atmosphere and means to burn a fuel and to supply the hot products of combustion directly to said heating flues.

3. Apparatus of the type described, which comprises a hollow structure having vertical hollow ribs extending laterally from a common central water chamber and spaced to form channels open at one edge to the atmosphere, vertical walls in said channels to form heating flues in said channels and to leave the outer edges of the channels open to the atmosphere and a furnace below said water chamber having a fire box opening directly into said flues.

4. A combined heater and radiator comprising a sheet metal vessel for water to be heated, the wall of said vessel being in the form of a series of spaced hollow ribs, the interiors of which communicate with the central portion of the vessel, partition walls in the spaces between said ribs forming passages for heating gases through the innermost portions only of said spaces between said ribs to heat the water in the vessel, the outer portions of the spaces between said ribs being open to radiate heat to the surrounding atmosphere, and means for burning fuel and supplying the products of combustion to said heating gas passages.

5. A combined heater and radiator comprising a sheet metal vessel for water to be heated, the wall of said vessel being formed of a series of hollow ribs the hollows of which communicate with the central portion of the vessel and having spaces between said

ribs, lengthwise partition walls in the spaces between said ribs forming passages for heating gases through the internal portions only of said spaces to heat the water in the vessel, the outer portions of said ribs being exposed to radiate heat to the surrounding atmosphere, and a fire box below said vessel having its combustion space in communication with said passages, said fire box also having a hollow wall for water in communication with the water space in the first mentioned vessel.

In witness whereof, I have hereunto signed my name.
